UNITED STATES PATENT OFFICE.

ALBERT C. MENGES, OF MEMPHIS, TENNESSEE.

AUTOMOBILE HOIST.

Application filed January 2, 1926. Serial No. 79,050.

This invention relates to automobile hoists and the like and more particularly to a structure of this character employing as a hoisting means a rotatable jack shaft and 5 an operating motor therefor.

An important object of the invention is to provide a mounting for the operating motor such that the weight thereof is centralized to the structure and the structure 10 may accordingly be properly balanced.

A further object of the invention is to provide a device of this character including a rotatable jack shaft, a motor axially aligned with the jack shaft and planetary 15 gearing interposed between and connecting the jack shaft and motor.

A still further object of the invention is to provide a device of this character in which the housing of the planetary gearing 20 provides a support for a housing sleeve for the jack shaft protecting the jack shaft from the entry of dust and dirt.

These and other objects I attain by the construction shown in the accompanying 25 drawings, wherein for the purpose of illustration is shown a preferred embodiment of my invention and wherein:—

Figure 1 is a plan view of hoisting apparatus constructed in accordance with my 30 invention;

Figure 2 is an enlarged vertical sectional view therethrough;

Figure 3 is a plan view partially in section showing one of the units.

Referring now more particularly to the drawings, the numeral 10 generally designates a vehicle receiving platform including bracing beams 11. These bracing beams combine to support a hollow casting 12 formed centrally with a bore 13 receiving a motor housing 14. At the lower end of the bore, a shoulder 15 is produced limiting downward movement of the motor housing into the bore. A cap or closure 16 for the 40 upper end of the bore is provided, this cap having an end bearing 17 for the armature shaft 18 of the motor.

Secured to the under surface of the casing 12 is a cupped housing 19, the upper ends of 50 the side walls of which are provided with ears 20 through which securing elements attaching the same to the casing 12 and indicated at 21 are directed. In the bottom of this housing, a bearing 22 is formed co-axial 55 with the motor shaft 18 and this bearing receives the reduced upper end 23 of a thread-

ed jack shaft 24. Between the body of the jack shaft and the lower face of the cup-shaped housing, a thrust bearing 25 is introduced. Surrounding the shaft 24 is a 60 supporting tube 26 in the upper end of which is mounted a nut 27 through which the jack shaft 24 is threaded. The mounting for the nut includes an outwardly extending flange 28 which bears against the inner surface of a 65 housing sleeve 29, the upper end of which is fitted and secured to the outer walls of the cup-shaped housing 19. This sleeve is splined to a ring 30 which is supported from the housing 31 of the jack shaft. It will 70 be seen that as the structure above described elevates, the sleeve 29 will elevate therewith and through the ring 30 will maintain with the housing 31 a complete enclosure for the jack shaft, preventing the entry of dust and 75 dirt thereto.

The upper end of the reduced portion 23 of the jack shaft projects into the cup-shaped housing at the lower end thereof and has keyed thereto, as at 32, a disk 33 having secured thereto an orbit gear 34 mounted in the disk on pivots 35 upon which are mounted at the upper surface of the disk planet gears 36 meshing with the orbit gear 34. A similar disk 37 is provided with an axial 80 stub shaft 38 to which is secured a gear 39 forming the sun gear of this section of the train. The disk 37 is likewise provided with an orbit gear 40 and planet gears 41. The sun gear 42 of this train is secured to the 85 armature shaft 18 of the motor. This gear and the end of the armature shaft rest upon a thrust bearing 43 seated in an axial depression formed in the upper surface of the disk 37.

It will be obvious that by the structure recited, an even distribution of weight is afforded and that the jack shaft is driven from the motor at a much reduced rate of speed through the compound planetary train 100 provided by the disks 33 and 37 and their associated elements. It will also be obvious that the construction hereinbefore set forth is obviously capable of a certain range of change and modification without materially 105 departing from the spirit of the invention and I accordingly do not limit myself to such specific structure except as hereinafter claimed.

I claim:—

1. In a combined elevator and turntable for vehicles, a vehicle supporting structure, a

casting supported therefrom and having a centrally located motor housing, a motor arranged within the housing with its shaft vertically directed, planetary gearing operated from and arranged co-axially with said motor shaft, a housing for said gearing, a threaded jack shaft supporting the housing and an extension on said jack shaft projecting into the housing and operatively connected with said planetary gearing.

2. In a combined elevator and turntable for vehicles, a vehicle supporting structure, a casting supported therefrom and having a centrally located motor housing, a motor arranged within the housing with its shaft vertically directed, planetary gearing operated from and arranged co-axially with said motor shaft, a housing for said gearing, a threaded jack shaft supporting the housing and an extension on said jack shaft projecting into the housing and operatively connected with said planetary gearing, said jack shaft being co-axial with said motor shaft.

3. In a combined elevator and turntable for vehicles, a vehicle supporting structure, a casting supported therefrom and having a centrally located motor housing, a motor arranged within the housing with its shaft vertically directed, planetary gearing operated from and arranged co-axially with said motor shaft, a housing for said gearing, a threaded jack shaft supporting the housing, an extension on said jack shaft projecting into the housing and operatively connected with said planetary gearing and a housing sleeve supported from the housing of the planetary gearing and surrounding said motor shaft.

4. In a combined elevator and turntable for vehicles, a vehicle supporting structure, a casting supported therefrom and having a centrally located motor housing, a motor arranged within the housing with its shaft vertically directed, planetary gearing operated from and arranged co-axially with said motor shaft, a housing for said gearing, a threaded jack shaft supporting the housing, an extension on said jack shaft projecting

into the housing and operatively connected with said planetary gearing, the planetary gearing including a pair of disks each having an orbit gear and planet gears associated therewith, one of said disks being secured to said jack shaft, the other of the disks having a sun gear for the first named disk and a sun gear for the last named disk secured to said motor shaft.

5. In a combined elevator and turntable for vehicles, a vehicle supporting structure, a casting supported therefrom and having a centrally located motor housing, a motor arranged within the housing with its shaft vertically directed, planetary gearing operated from and arranged co-axially with said motor shaft, a housing for said gearing, a threaded jack shaft supporting the housing, an extension on said jack shaft projecting into the housing and operatively connected with said planetary gearing, the planetary gearing including a pair of disks each having an orbit gear, planet gears associated therewith, one of said disks being secured to said jack shaft, the other of the disks having a sun gear for the first named disk and a sun gear for the last named disk secured to said motor shaft and a thrust bearing interposed between the sun gear of the motor shaft and the last named disk.

6. In a combined elevator and turntable for vehicles, a vehicle supporting structure, a casting supported therefrom and having a centrally located motor housing, a motor arranged within the housing with its shaft vertically directed, planetary gearing operated from and arranged co-axially with said motor shaft, a housing for said gearing, a threaded jack shaft supporting the housing, an extension on said jack shaft projecting into the housing and operatively connected with said planetary gearing, and a thrust bearing interposed between the jack shaft and the housing of said planetary gearing.

In testimony whereof I hereunto affix my signature.

ALBERT C. MENGES.
